Application June 15, 1931, Serial No. 544,662,
and in Belgium June 23, 1930

18 Claims. (Cl. 261—49)

This invention concerns a carburetor whereby light or heavy liquid fuels may be gasified for feeding, in particular, internal combustion engines under conditions ensuring a very low fuel consumption.

According to the invention, the air to be carbureted sucks from a ring shaped aperture, surrounding the apex of an inverted cone or like convex body, a thin annulus of fuel which it carries upwards, whilst spreading the same upon the flaring surface of the cone in a film of progressively diminishing thickness, which it absorbs by contact. The air to be carbureted is preferably divided into two concentric streams of which the inner stream, of small cross-section, impinges at high speed against the apex of the said cone to suck up the fuel, whilst the outer or peripheral stream joins the central or inner stream beyond the apex and sweeps the surface of said cone, together with the inner stream. Carbureting is then controlled, during normal running of the motor, by throttling or releasing both concentric streams of air simultaneously whilst, during slow or idle running, the outer or peripheral air stream is entirely cut off. It may in some cases be desirable to cause the air which sweeps the spreader cone to be whirled.

In a carburetor constructed to embody the principles of said process, the inverted cone is fitted above a jet fed from a constant level chamber or otherwise, the mouth of said jet surrounding the apex of the cone and opening axially inside the constriction of a choke tube. The delivery of fuel from the jet is regulated by moving the apex of the cone inwards or outwards of the jet mouth, whilst the air supply to the choke-tube is controlled by means of a conical valve surrounding the jet and mounted to slide axially. Said inlet valve is connected with an outlet valve adapted to move simultaneously therewith, to control the vacuum at the outlet of the choke tube, said outlet valve also acting as a deflector of the air and fuel mixture.

The air to be carbureted may be admitted within the choke tube around the inlet valve only, but it is preferable to admit it both around said valve and through the same, in order to divide the air into two concentric streams, as stated above. In this case, the conical valve is tubular in shape and its truncated apex coacts with the point of the spreader cone to throttle the inner, central or primary air stream, whilst its dished base throttles the outer, peripheral or secondary air stream by obstructing the choke tube inlet. For slow or idle running of the motor, the valve

closes the secondary air inlet completely and only allows the passage of the quantity of primary air which is essential for continued withdrawal of fuel from the jet.

The outlet valve, which moves jointly with the inlet valve, may furthermore move towards the choke tube independently of the inlet valve so that, if back-firing takes place at the carburetor, said outlet valve is impelled by the pressure of the ignited gas to close the choke tube outlet and thus prevent the flame from spreading within the carburetor. On the other hand, to avoid useless fuel consumption when the motor revolves idly at high speed, when running downhill for instance, the jet is fitted with a valve, actuated by the vacuum obtaining in the motor induction manifold, to cut off the fuel feed to the jet as soon as said vacuum exceeds a predetermined value.

The abovementioned features of the invention and some others will now be described with reference to the accompanying drawing which shows, by way of example, one constructional embodiment of the carburetor.

Fig. 1 is a vertical section of the carburetor, partly in side elevation, the parts being in the slow or idle running positions;

Fig. 2 is a partial view of Fig. 1, showing the inlet valve fully opened;

Fig. 3 is a vertical section of the jet, showing the consumption restricting valve in its closed position for idle running;

Fig. 4 is a cross section of a further detail.

In said drawing, 1 is the inverted or spreader cone whose apex 2 enters the centre of the mouth 3 of jet 4, and 5 is the choke tube surrounding these members. The inlet to choke tube 5 is controlled by a conical tubular valve 6, axially slidably round jet 4 and connected with an outlet deflector-valve 8, fitted within an auxiliary choke tube 9 constituting an extension of choke tube 5. All these members are contained in a housing, the upper part 12 of which forms a reheating jacket surrounding the choke tubes. The lower portion 13 of said housing forms a constant-level chamber for the fuel to feed jet 4. A ring-shaped float 14, controlling the inlet valve 15 of said chamber, so regulates the fuel level that it is flush with mouth 3 of the jet.

The constant-level chamber 13 is connected with jet 4 by means of ducts 23, drilled through the arms 24 of a cruciform member, integral with the chamber walls, said ducts opening in a central space 25, which is closed by means of a screw-plug 26 and contains a ball 28 and a spring 110

27 adapted to apply the latter against the mouths of ducts 23 and to occlude them when the jet is dismounted. The ball 28 is normally held clear of its seating by a tubular screw 29, screwed 5 within jet 4, and fuel may ascend in the jet by entering the tubular screw through slots 30 in the base of the same, passing through a sleeve 31 fitted slidably in the jet and streaming towards the annular mouth 3 of the jet through ports 32, 10 provided in the wall of said sleeve.

The upper portion 31' of sleeve 31 which is made integral with the point 2 of the spreader cone 1, is constricted in order to provide the requisite space between itself and the jet for the 15 flow of fuel towards mouth 3. As the drawing shows, the point 2 is not even but comprises a point-stem 2a from which it is separated by an acutely angled groove 33. The conicity of the point-stem 2a is more acute than that of point 2 20 and, hence, than that of cone 1 and is preferably so calculated that extensions of its sides would intersect the walls of cone 1 at the point where the latter joins point 2, the shoulder constituted by groove 5 being substantially flush with the lip 25 of jet mouth 3.

The section of the annular mouth 3 and consequently the fuel supply from the jet are regulated by lifting the latter from its conical seating 34 and by screwing or unscrewing the tubular screw 30 29 to a varying degree within the jet, according to the adjustment required, thereby moving towards or away from mouth 3 the point-stem 2a, which acts as a needle and to which the motion of screw 29 is transmitted by sleeve 31. A spring 35, contained within cone 1, bears against point 2 35 through a sleeve 36 and presses said point downwards, together with sleeve 31, to hold the latter in contact with screw 29.

The other end of the spring 35 bears against a 40 threaded ring 37, screwed within a tube 38, which forms an upward extension of the conical valve 6 and carries the deflector valve 8. Tube 38 passes smoothly through a central bore of the spreader cone 1, within which it is adapted to slide 45 round sleeve 36 and point 2, carrying with it the two valves 6 and 8 of which the latter is pressed against a rim 40 of ring 37, screwed within said tube. Ring 37 is integral with and is surmounted by a stirrup piece 41, carrying a roller 42 against 50 which bears a control lever 43 actuated, through a rod 44, for example, by the accelerator pedal of the engine.

When said lever 43 depresses roller 42, the tube 38 and both valves 6 and 8 move downwards, compressing spring 35, bearing against stationary sleeve 36, and place themselves either in the full-open 55 valve position shown in dots and dashes in Fig. 1 and in full lines in Fig. 2, or in an intermediate position dependent upon the amount of movement 60 imparted to lever 43. Upon said lever being released, spring 35 returns the tube and valves to the closed position.

A plurality of elongated ports 45, provided at the base of tube 38, are so occluded by cone 1, 65 when the valves are in the closed position, that only a small portion of their lower ends remain open. They are uncovered when the tube emerges from the cone and open progressively, as the valves approach their full open position. Together with valves 6 and 8, said ports control the 70 action of the carburetor and the richness of the mixture which is fed to the induction of a motor coupled to outlet 20 of the device.

In order to make the working of the apparatus 75 clear, it will be assumed firstly that valves 6 and

8 and ports 45 are open, as is shown in dots and dashes in Fig. 1 and in full lines in Fig. 2.

Outside air is sucked by the motor, enters the base of the carburetor between the arms of cruciform piece 24 and flows into the choke tube 5. When entering the latter, it is divided into two concentric streams of which the first, or primary, passes within conical valve 6 and the second, or auxiliary, flows into the annular space comprised between cone 6 and choke tube 5. The primary air stream, to which a high speed is imparted by the narrowness of the inner channel of cone 6, carries the thin annulus of fuel standing flush with mouth 3 of jet 4 on to point-stem 2a, thence on to point 2 and on to spreader cone 1, through ports 45. The gap formed by groove 33 sets up, behind the point-stem 2a, a vacuum which assists in sucking fuel from the jet.

Upon leaving ports 45, the fuel-charged primary air stream joins the auxiliary air stream and both spread the fuel upon cone 1 in a film of progressively decreasing thickness until it is vaporized. The mixture of fuel and air thus made impinges, beyond the cone, against stationary, inclined and specially shaped vanes 46 (Figs. 1 and 100 4), which cause it to whirl, in which condition it enters the auxiliary choke tube 9, passes round deflector 8 and flows towards outlet 20 and the induction manifold of the engine.

Vanes 46, which may be integral with a disc 47 supporting spreader cone 1, are held by hollow screws 48, by means of which these two members are suspended from the inner wall of the reheating jacket 12. Said screws being hollow also serve to connect said jacket with an inner cavity 49 of cone 1. On the other hand, jacket 12 communicates by means of ducts 50 with a jacket 51, surrounding choke tube 5, so that the warming fluid entering through pipe 52 and discharging through pipe 53 flows, not only within jacket 12, but within 115 cone 1 and jacket 51 likewise. The mixture of air and fuel is thus reheated from all sides, whilst flowing through the carburetor.

It will be clear that the quantity of air and fuel admitted to the motor, and consequently the running of the latter, may be regulated by varying the position of valves 6 and 8 by means of control lever 43. When said parts are in the upper position indicated in full lines in Fig. 1, which corresponds with slow or idle running of the motor, 120 deflector 8 almost wholly closes outlet 20 and thus throttles the motor induction, whilst valve 6 wholly closes the mouth of choke tube 5, cutting off auxiliary air. A small amount of primary air can alone pass through ports 45, which are almost 125 entirely occluded by cone 1, in which tube 38 is telescoped.

The motor is accelerated by actuating lever 43, to the extent required, to depress deflector 8 which uncovers outlet 20, tube 38 whose ports are further uncovered and allow the passage of a larger quantity of primary air and valve 6, which opens the mouth of choke tube 5, thereby allowing auxiliary air to enter. Maximum acceleration is reached when the controlling members are in the 130 lower position, shown in dots and dashes in Fig. 1.

According to the type of fuel used, slow or idle running may be regulated by varying the section of the passage remaining free between the deflector valve 8 when in its upper position, and the 145 overhanging wall of auxiliary choke chamber 9, so as to strengthen or to reduce engine suction. This adjustment is effected by screwing or unscrewing, within tube 35, the ring 37 against whose rim 40 the deflector bears.

Said deflector valve 8 is adapted to slide on tube 38 and is normally pressed against rim 40 by the spring 39, but if back firing should take place, in the engine induction manifold for instance, the pressure of the ignited gas upon the upper face 5 of deflector 8 would drive the latter downward against the inlet to auxiliary choke-chamber 9, as shown at 8a in Fig. 1, in which position deflector 8 acts as a check valve and prevents the ignited gas from reaching the carburetor and setting fire to the same. A safety valve 54 opening from outlet 20 may be provided, comprising a spring so weighted that the valve opens to allow the escape of the gases, should pressure within choke tube 9 become excessive.

As stated above, the carburetor likewise comprises automatic means for cutting off the supply of fuel from the jet, should the motor revolve idly at high speed in spite of valves 6 and 8 being closed, when the motor is revolved by the road wheels of a car proceeding under momentum or running downhill, for example. The effect of the high degree of vacuum created, in such a case, within the induction manifold of the engine and within the carburetor itself, by the circumstance that valve 6 is wholly closed whilst valve 8 remains slightly open, would be to draw an excessive quantity of fuel from jet 4 and to cause wasteful consumption of the same, if steps were not taken to avert this contingency.

Within sleeve 36, hereinbefore mentioned, a small piston 55 is adapted to slide, to which is secured a needle 56 extending axially through the constricted portion of sleeve 31 and ending in a club shaped head 57, normally hanging within the wide portion of the sleeve but adapted to close the constricted portion when retracted into the same by an upward movement of piston 55 (Fig. 3). The latter is kept depressed by a light spring 58 and its stroke is limited in an upward direction by an adjustable stop consisting of a screw 59, threaded into a needle 60, which provides a seating for spring 58 and is, itself, supported centrally, by means of a crosspiece, within a threaded ring 61. Above said needle 60 is fitted a second, hollow, threaded needle 62, through which are bored ports 63 connecting the interior of sleeve 36 with the outlet 20 of the carburetor, through ring 37, whose lower portion constitutes a conical seating adapted to fit needle 62. The position of needle 62 in relation to needle 60 and the width of the passage left between these two members, may be adjusted by screwing needle 62 more or less deeply into the inwardly threaded portion of sleeve 36.

When valves 6 and 8 are closed and the engine is running idly at high revolutions, the vacuum within outlet 20 soon becomes considerable and spreads to the interior of sleeve 36, to the extent regulated by needle 60 and 62. As soon as said vacuum is sufficiently strong to overcome spring 58, piston 55 rises in sleeve 36 and carries with it needle 56, whose head 57 rises to obstruct the constricted portion of sleeve 31, thereby cutting off fuel from the jet to an extent governed by the position of the screw-stop 59.

On the other hand, should the slowing down of the engine cause the vacuum to decrease, then spring 58 repels piston 55 and needle 56 again clears the duct of the jet. The same thing happens when valves 6 and 8 are opened by depressing tube 38 since, in this case, the seating 64 of ring 37 moves towards needle 62, thereby throttling the passage between outlet 20 and the interior of sleeve 36 and reducing or removing the

vacuum which actuated piston 55. Small ports 65, provided in the base of sleeve 36, prevent the formation of a gas cushion at the bottom of the same, which might impede the movements of piston 55.

To start the motor, fuel chamber 13 may be flooded by depressing float 14 by means of tickler-pin 66.

It is to be understood that the generant of the spreader cone 1 need not be straight but might be constituted by any curve adapted to generate a suitably shaped body, the word cone, as used in the appended claims, being understood to cover any flaring body having a surface suitable for spreading a liquid in accordance with the principles of this invention. The invention is not, therefore, limited to the constructional details hereinbefore described by way of example, as said details may be varied without departing from the scope of the appended claims.

I claim:

1. In a carburetor, the combination of an inverted cone, a jet co-axial with said cone, said jet having an annular opening surrounding the apex of said cone, a choke tube surrounding said jet and said cone, air supply passages connected to the inlet end of said choke tube, and annular means in said choke tube for directing a flow of primary air across said jet opening and a flow of secondary air around said flow of primary air. 105

2. In a carburetor the combination of an inverted cone, a jet co-axial with said cone, said jet having an annular opening surrounding the apex of said cone, a choke tube surrounding said jet and said cone, an annular valve in said choke tube surrounding said jet said valve co-operating with said cone to form a primary air passage and with said choke tube to form a secondary air passage, and means for moving said valve axially in said choke tube and thereby simultaneously 115 varying the cross-sectional areas of both said passages.

3. In a carburetor the combination of an inverted cone, a jet co-axial with said cone, said jet having a delivery opening surrounding the 120 apex of said cone, a choke tube surrounding said jet and said cone, a hollow conical valve surrounding said jet, the upper edge of said valve co-operating with said cone to regulate a flow of primary air therebetween, the lower edge of said 125 valve co-operating with the wall of said tube to regulate a flow of secondary air therebetween, a chamber connected with the outlet end of said choke tube, a deflector valve in said chamber, and means operatively connecting both said 130 valves with each other.

4. In a carburetor, the combination of an inverted cone, a jet co-axial with said cone, said jet having a delivery opening surrounding the apex of said cone, a choke tube surrounding said jet and said cone, a hollow conical valve in said choke tube surrounding said jet, said conical valve being so arranged in the choke tube that in its depressed position two air passages are formed in said tube, one being a narrow passage between the said inner wall of valve and the jet, the other a wider passage between the outer wall of said valve and the choke tube, said valve being adapted to check the flow of air through both said passages when in its elevated position. 140

5. In a carburetor the combination of an inverted cone, a jet co-axial with said cone, said jet having a delivery opening surrounding the apex of said cone, a choke tube surrounding said jet and said cone, a hollow conical valve sur- 150

- rounding said jet, said valve being adapted to check the flow of air through said tube, a chamber connected with the outlet end of said choke tube, a deflector valve in said chamber, means 5 operatively connecting both said valves with each other, said means comprising a tubular carrier mounted in an axial bore of said cone, the end of said carrier adjacent the conical valve having narrow longitudinal ports, said ports remaining 10 slightly open when the conical valve is in its elevated position.
6. In a carburetor as claimed in claim 5, a spring within the tubular carrier, said spring normally holding said carrier and both valves 15 in their elevated positions, and means for depressing said carrier with the valves against the tension of said springs.
7. In a carburetor as claimed in claim 3, spring means for allowing the deflector valve to move 20 towards the cone independently of the conical valve, and a seating adapted to receive said deflector valve in its lowermost position, said seating being interposed between the choke tube and the outlet chamber.
- 25 8. In a carburetor as claimed in claim 5, the deflector valve being slidably mounted on its tubular carrier, an adjustable abutment adjustably fitted at the top of said carrier, and a coil spring interposed between the cone and the deflector valve, said valve being normally held in contact with said abutment by said spring.
- 30 9. In a carburetor, the combination with the elements recited in claim 3, with means influenced by the vacuum above the deflector valve 35 for cutting the supply of fuel through the jet when said vacuum exceeds a given limit.
10. In a carburetor the combination of an inverted cone, a jet co-axial with said cone, said jet having a delivery opening surrounding the 40 apex of said cone, a choke tube surrounding said jet and said cone, a hollow conical valve surrounding said jet, said valve being adapted to check the flow of air through said tube, a chamber connected with the outlet end of said choke 45 tube, a deflector valve in said chamber, means operatively connecting both said valves with each other, means influenced by the vacuum above the deflector valve for cutting the supply of fuel through the jet when said vacuum exceeds 50 a given limit, the vacuum influenced means comprising a spring controlled piston in an axial bore of the cone, and a member extending through the apex of the cone into the jet.
- 55 11. In a carburetor as claimed in claim 10, adjustable means for varying the action on the piston of the vacuum above the deflector valve.
12. In a carburetor as claimed in claim 5, a spring controlled piston in the tubular carrier, a hollow member fitted at the end of the cone, 60 said member extending axially into the jet, ports in said hollow member, said ports controlling the passage of the fuel through the jet, and a club-shaped member adjustably connected to said piston, said club-shaped member extending 65 through said hollow member, said piston being subjected to the vacuum above the deflector valve, said club-shaped member being adapted to close said ports when said piston is drawn upwards by the action of said vacuum.
- 70 13. In a carburetor, the combination of an inverted cone, a jet beneath said cone and co-axial therewith, said cone having a downwardly projecting point projecting into said jet, said point forming with the upper edge of said jet an annular orifice for the delivery of liquid fuel, a 75 choke tube surrounding said jet and said cone, said annular orifice opening into the constricted portion of said choke tube, the inlet end of said choke tube being open to the atmosphere, an annular valve in said choke tube surrounding said orifice, the upper edge of said valve cooperating with said cone to direct a flow of primary air across said orifice the lower edge of said valve cooperating with said choke tube to direct a flow of secondary air around said valve, and means for varying the relative positions between said cone and said jet. 80
14. In a carburetor, the combination of an inverted cone, a jet beneath said cone and co-axial therewith, said jet having a delivery opening surrounding the apex of said cone, a choke tube surrounding said jet and said cone, the inlet end of said choke tube being open to the atmosphere, means for varying the flow of air through said choke tube, a suction chamber connected with the outlet end of said choke tube, and means influenced by the vacuum in said suction chamber for automatically cutting off the supply of fuel through said jet. 85
15. In a carburetor as claimed in claim 14, the suction chamber and the cone having hollow walls respectively forming a jacket around said suction chamber and a jacket within said cone, tubular passages connecting said jacket with each other, and pipe connections for circulating a heating fluid through said jackets. 90
16. In a carburetor, the combination of an inverted cone, a jet beneath said cone and co-axial therewith, a choke tube surrounding said jet and said cone, said jet having an annular orifice for the delivery of fuel, said orifice opening into the constricted portion of said choke tube, and an annular valve in said choke tube surrounding said jet, the upper edge of said valve co-operating with said cone to form a primary air passage, the lower edge of said valve co-operating with said tube to form a secondary air passage. 95
17. In a carburetor, the combination of an inverted cone, a jet co-axial with said cone, said jet having an annular opening underneath said cone, a choke tube surrounding said jet and said cone, the inlet end of said tube being connected with the atmosphere, an annular valve in said choke tube surrounding said jet, the upper edge of said valve co-operating with said cone to form a primary-air passage, the lower edge of said valve co-operating with said tube to form a secondary air passage, means for depressing said valve, the arrangement being such that on said valve being depressed the cross-sectional area of said secondary air passage increases more rapidly than that of said primary air passage. 100
18. In a carburetor, the combination of an inverted cone, a jet beneath said cone and co-axial therewith, a choke tube surrounding said jet and said cone, the inlet end of said choke tube being open to the atmosphere, said jet having an annular orifice for the delivery of fuel, said orifice opening into the constricted portion of said choke tube, means in said choke tube for dividing the air flowing therethrough into a flow of primary air sweeping across said orifice and a flow of secondary air surrounding said flow of primary air, and means for imparting a whirling motion to the air issuing from said choke tube. 105

ANDRÉ MATHIEU.
